UNITED STATES PATENT OFFICE

LARA ESTES OSBORN, OF ESTES PARK, COLORADO.

HYDROCARBON-BURNER.

1,109,867.

Specification of Letters Patent.

Patented Sept. 8, 1914.

Application filed May 23, 1914. Serial No. 840,613.

To all whom it may concern:

Be it known that I, LARA ESTES OSBORN, a citizen of the United States, residing at Estes Park, in the county of Larimer and State of Colorado, have invented a new and useful Hydrocarbon-Burner, of which the following is a specification.

The present invention appertains to liquid fuel or hydro-carbon burners, and aims to provide a novel and improved burner adapted particularly for consuming kerosene and gasoline and applicable in the fire pot of a cooking or heating stove, furnace, or the like.

15 The present invention contemplates the provision of a burner of the nature indicated, embodying a unique construction and combination of its component parts, whereby the utility of the burner will be enhanced.

20 Another object of the present invention is to provide a burner including a secondary or pilot burner, combined therewith in a novel manner, and adapted for priming the generator and for igniting the gas issuing 25 from the main burner.

It is also within the scope of the present invention, to provide a burner of comparatively simple, compact, durable and inexpensive construction, which will serve to mix 30 the air with the evaporized fuel in a thorough manner, so that the combustion of the gaseous mixture will produce a maximum heating effect with a minimum amount of fuel, and which will be improved generally 35 in its construction.

With the foregoing and other objects in view which will appear as the description proceeds, the invention resides in the combination and arrangement of parts and in 40 the details of construction hereinafter described and claimed, it being understood that changes in the precise embodiment of the invention herein disclosed can be made within the scope of what is claimed without 45 departing from the spirit of the invention.

The invention has been illustrated in its preferred embodiment in the accompanying drawing, wherein:

50 Figure 1 is a plan view of the improved burner. Fig. 2 is an enlarged cross section taken on the line 2-2 of Fig. 1. Fig. 3 is an enlarged longitudinal section taken on the line 3-3 of Fig. 1, portions being broken away. Fig. 4 is a longitudinal section of the 55 secondary or pilot burner, taken on the line 4-4 of Fig. 2.

The body or casing of the present burner includes an upper casing or top plate 1 having a plurality of longitudinal parallel corrugations, three in number, and providing the ridges 2 and furrows or valleys 3 therebetween. The ridges 2 are provided with transverse slots or kerfs 4 providing outlets for the gaseous mixture. Each of the ridges 2 is provided with a series of the 60 slots or outlets 4, whereby the flames will be distributed over practically the entire area of the burner body or casing, as will be apparent by reference to Fig. 1.

The burner body or casing further includes a lower casing or bottom plate 5 which is bolted or otherwise fastened to the edges and ends of the upper casting or plate 1. The forward or outer end 6 of the body or casing is preferably extended above the 70 upper casting or plate 1 to provide a shield or guard, as most clearly seen in Fig. 3. The body or casing is of such construction, that it may be readily set upon the grate at the bottom of the fire pot of a cooking or 75 heating stove, although it is to be understood that the burner may be employed in divers capacities.

As a means for thoroughly mixing and spreading the gaseous mixture within the 80 body or casing, a diaphragm or partition plate 7 is disposed between and extends to the sides of the upper casting 1, the sides of the upper casting 1 being preferably provided with supporting flanges or ledges 8 85 upon which the edge portions of the diaphragm or plate 7 rest. The diaphragm or plate 7 extends from the rear or inner end of the body or casing to a point short of the forward or outer end 6, to provide an opening 9 at the forward end of the casing establishing communications between the forward or outer ends of the chambers above and below the diaphragm or partition plate 7. The diaphragm or plate 7 is preferably 90 disposed adjacent the furrows or valleys 3 of the casting or top plate 1.

The outer or forward end 6 of the body or casing is provided with a longitudinal inwardly projecting mixing tube 10 extending 105 below the forward end of the diaphragm or plate 7 midway between the sides of the body or casing, whereby the evaporized fuel and air forced through the mixing tube 10 will first be forced below the diaphragm or 110 partition plate 7 and will thence pass forwardly and upward through the opening 9

into the chamber or space above the diaphragm or plate 7 to pass through the discharge slots or openings 4.

The supplemental or pilot burner comprises an elongated casing or body 11 of diamond-shaped cross section, and fitting within one of the furrows or depression 3. A series of slots or kerfs 12 are cut or sawed in the ridge of the casting or body 11 to provide outlets for the gaseous mixture introduced into the body or casing 11.

A diaphragm or partition plate 13, which is elongated, is fitted between the sides of the body or casing 11, and the outer or forward end of the body or casing 11, has an inwardly projecting mixing tube 14, extending below the diaphragm or plate 13, the diaphragm or plate 13 being apertured, as clearly seen in Fig. 4.

20 The generators or retorts for the main and auxiliary burners, embody supply pipes 15 and 16, respectively, which are connected to any suitable source of liquid fuel, and which extend longitudinally over the auxiliary or pilot burner and the corresponding valley 3 of the main burner. Rods 17 are preferably extended through the generator or retort portions of the pipes 15 and 16, which are disposed above the main and auxiliary burners, whereby the rods 17 facilitate the generation of the vapor or the evaporation of the liquid fuel.

25 The forward or outward ends of the tubes 15 and 16 are downturned or deflexed, as at 18 and 19, respectively, and cruciform valve casings 20 and 21 have their upper arms engaged to the respective depending angular ends 18 and 19 of the supply or generator pipes. The inwardly projecting arms 22 and 23 of the cruciform valve casings 20 and 21, respectively, are in the form of nozzles projecting into the mouths or outer ends of the respective mixing tubes 10 and 11, while needle valves 24 are threadedly or adjustably engaged through the outwardly projecting arms of the casings 20 and 21, to co-operate with the outlet apertures or ducts of the nozzles 22 and 23 for controlling the discharge of vapor into the respective mixing tubes.

50 In practice, the present device may be readily applied to the fire box of a cooking or heating stove, or to other structures to be heated. In starting the burner, the fuel is first admitted into the supply and generator pipe 16 of the auxiliary or pilot burner, and the generation of the vapor may be started by heating the pipe 16 in any suitable manner. The evaporized fuel may 55 then be discharged into the mixing tube 14 of the auxiliary or pilot burner, by properly controlling the corresponding needle valve 24. As the vaporized fuel is injected into the body or casting 11 of the auxiliary or secondary burner, air will be drawn into

the mixing tube 14 to commingle with the fuel, the air and fuel being thoroughly mixed and spread under the diaphragm or partition 13, as will be obvious, and the mixture will rise through the apertures in the 70 diaphragm 13 throughout the length of the same. The mixture will then pass outwardly through the slots or outlets 12 for supporting the pilot flames, which will heat both of the pipes 15 and 16 for continuing 75 the generation of the vapor within the pipe 16, and for starting the generation of the vapor within the main pipe 15 when the fuel is admitted into the main pipe 15, and is 80 generated by the pilot flames, the main burner may be readily started, by opening the needle valve 24 of the casing 20, which will cause the vaporized fuel to be injected into the bottom portion of the main body 85 or casing, and at the same time, air will be drawn into and through the mixing tube 10 with the fuel to commingle with the fuel under the diaphragm or partition 7. It is evident that the air and fuel in being forced 90 under the diaphragm 7, will cause the same to thoroughly admix, the diaphragm 7 also serving as a spreader for the mixture. The gaseous mixture will then pass upwardly, through the opening 9 and along the various corrugation or ridges 2 to pass upwardly through the slots or outlets 4 for supporting the main flames throughout the area of the main burner. After the auxiliary or pilot burner has been started, the 100 same may be operated continually, whereby the main burner may be brought into and out of operation, at will, and without the necessity of priming the main burner by hand, and without the necessity of igniting 105 the gas by hand. It is possible, however, to shut off the auxiliary or pilot burner during the operation of the main burner, the auxiliary or pilot burner being readily started just prior to the shutting off of the main burner, if desired, in order that the main burner may be readily started at a subsequent time.

110 From the foregoing, taken in connection with the drawing, the other advantages and attributes of the present invention will be obvious to those versed in the art without further comment being necessary.

Having thus described the invention, what is claimed as new is:—

1. A burner embodying a casing having upper outlets, a diaphragm within the casing and extending to the sides and one end thereof, there being an opening between the other end of the casing and diaphragm, and a mixing tube carried by the last mentioned end of the casing and projecting under the diaphragm.

2. A burner comprising a casing, the top of which is provided with longitudinal cor-

rugations, the ridges of the corrugations having outlets, a diaphragm disposed within the casing adjacent the furrows of the corrugations, the diaphragm extending to the 5 sides and one end of the casing, there being an opening between the other end of the casing and the diaphragm, and a mixing tube carried by the last mentioned end of the casing and projecting under the diaphragm.

10 3. In a device of the character described, a main burner including a casing, the top of which is provided with corrugations having outlets in their ridges, a pilot burner including an elongated casing seated within 15 one of the furrows of the corrugations and having longitudinal series of upper outlets,

a longitudinal perforated partition disposed between the sides of the pilot burner casing, and a pair of generators disposed above the pilot burner, one generator communicating 20 with the interior of the main burner casing, and the other generator communicating through one end of the pilot burner casing below the said partition.

In testimony that I claim the foregoing as 25 my own, I have hereto affixed my signature in the presence of two witnesses.

LARA ESTES OSBORN.
